UNITED STATES PATENT OFFICE.

JOSEPH SUTKAY, OF GARY, INDIANA.

ELECTRIC BOMB.

1,321,259.

Specification of Letters Patent. Patented Nov. 11, 1919.

Application filed July 30, 1918. Serial No. 247,398.

To all whom it may concern:

Be it known that I, JOSEPH SUTKAY, a citizen of the United States, residing at Gary, in the county of Lake and State of Indiana, have invented certain new and useful Improvements in Electric Bombs, of which the following is a specification.

The primary object of the invention is to improve the construction of a bomb adapted for employment in any suitable location in the enemy's territory to be discharged from a distant point electrically at any time desired.

With this general object in view, the device consists of the novel form, combination and arrangement of parts which will be hereinafter fully described in connection with the accompanying drawing and in which like designating characters refer to corresponding parts throughout the several views.

In the drawing,

Figure 1 is a top plan view of a plurality of the bombs electrically connected for distant discharge;

Fig. 2 is a central longitudinal sectional view of one of the bombs;

Fig. 3 is a perspective view of the holder for the explosive removed from the casing; and

Fig. 4 is a transverse sectional view taken upon line IV—IV of Fig. 2.

My invention contemplates improvement of explosive bombs adapted to be discharged from a distant point. This improvement includes the provision of a metallic ovoidal two-part bomb casing 10 having the parts or sections thereof screw-threaded together, as at 11, for retaining the contents within the casing after it is filled as hereinafter explained.

A bag 12 of suitable inflammable material such as canvas, is adapted for holding explosive material 13, the said bag being suitable for insertion within the casing 10.

An axial bore or opening 14 is provided through the bag 10 through which a tube 15 is inserted, perforations 16 being provided through said tube to permit transmission of sparks in any well known manner from the electric wire 17 to the explosive 13.

As herein shown, the sparks are transmitted from the electric wire 17 to the explosive 13 by means of the inflammable powder 17.

As the bag 12 is made of inflammable material, it is obvious that the sparks will reach

the explosive 13. The outer section 18 of the casing 10 is provided with a neck 19 having an axial bore 20 through which the fuse or wire 17 extends, while a curved washer 21 mounted upon the free end of said neck has the wire 17 passing through an opening 22 thereof at one side of the center of the washer. A cap 23 is threaded upon the neck 19 having a central opening 24 in its outer end for accommodating the wire 17, it being understood that by screwing the cap 23 upon the neck 19, a portion of the wire 17 is clamped between the washer 21 and cap 23 thereby holding a suitable length of the wire 17 within the tube 15.

When a plurality of the bombs are employed, the wires 17 are attached to a main wire 25 leading to any distant point or station so that all of the bombs may be simultaneously exploded. The wire 17 is preferably formed of a plurality of insulated strands having their bared ends spaced apart within the tube 15 for producing a spark within the tube upon closing an electrical circuit at the distantly positioned firing station. With a plurality of the bombs obscured from view beneath the ground and connected by means of the wires 17 and 25 with a distant point, it will be understood that when the enemy reaches a position above the bombs, a closing of the circuit for said wires will explode all of the bombs simultaneously for destroying the enemy.

What I claim as new is:—

1. In a bomb a two-part casing having an entrance neck, an explosive holding bag within said casing having a central opening therein in axial alinement with said neck, a perforated tube within said opening, a spark producing element extending through said neck into the tube, and a co-operating washer and cap detachably mounted upon said neck and engaging the spark producing element to retain a portion thereof within the tube.

2. In a bomb a casing formed of two sections threaded together, an entrance neck upon one of said sections at one end of the casing, a tubular canvas container arranged within and conforming to the internal shape of the casing, explosive material within the said container, a tube axially extending through the container and casing with its opposite ends engaging the ends of the sections of the casing and provided with ig-

nition perforations, a spark producing element extending through said neck into the tube, and retaining means for the spark producing element carried by said neck.

5 3. In a bomb a casing formed of two sections threaded together, an entrance neck upon one of said sections at one end of the casing, a tubular canvas container arranged within and conforming to the internal shape 10 of the casing, explosive material within the said container, a tube axially extending through the container and casing with its opposite ends engaging the ends of the sections of the casing and provided with ignition perforations, a spark producing element extending through said neck into the tube, a dished

washer upon the outer end of said neck having a perforation out of axial alinement with the neck and through which the spark producing element extends, and a cap 20 threaded upon the neck having an opening therethrough out of alinement with the opening of the washer, the spark producing element being extended through the opening of the cap whereby the tightening of 25 the cap upon the neck causes engagement of the cap and washer with the spark producing element for retaining a portion thereof within the tube.

In testimony whereof I affix my signature. 30

JOSEPH SUTKAY.
